HALLOWELL, OF PENFIELD, PENNSYLVANIA.

FLYING-MACHINE.

1,132,288.

Specification of Letters Patent. Patented Mar. 16, 1915.

Application filed February 18, 1910. Serial No. 544,573.

To all whom it may concern:

Be it known that I, EDWARD WANTON SMITH, a citizen of the United States, and a resident of the city of Philadelphia, 5 county of Philadelphia, and State of Pennsylvania, have invented certain new and useful Improvements in Flying-Machines, of which the following is a specification, reference being had to the accompanying drawings.

This invention particularly relates to flying machines of the class wherein the weight is sustained by one or more aeroplanes propelled through the air at a slight angle of incidence by any suitable power, or by the force of gravity.

In apparatus of this class, as heretofore constructed, the lateral stability is obtained by the relative twisting or warping of the 20 extremities of the wings, or of small auxiliary surfaces forming wing tips. The result in the relative change of resistance of the opposite sides of the machine effects a constant tendency to swerve from the straight 25 course, which must be overcome by operating the rudder simultaneously with the warping of the wings or wing tips. Thus, it may be seen that while the progress of the machine may not be directly retarded by 30 the warping of the plane or the auxiliary wing tips, it is materially retarded by the action of the rudder, which is swung against the air to maintain the machine in its course, when said warping or twisting is effected.

In this invention any tendency to unduly retard the progress of the machine or to 35 swerve said machine from the straight course due to the operation of the stabilizing mechanism is eliminated or rendered 40 negligible.

The principal objects of this invention are, to provide means for maintaining the lateral stability of a flying machine, without increasing the resistance of the forward 45 progress of said machine; to provide means to vary the effective weight supporting surface of the respective outer margins or wings of the aeroplane of said machine, without effecting the rigidity of said aeroplane; and to provide means whereby the 50 increase in effective weight supporting surface at one end of said aeroplane contemporaneously effects a similar decrease in the effective weight supporting surface at the

other end of said plane, without producing 55 a tendency in the machine to swerve from the straight course.

The preferred form of this invention hereinafter described, comprises a substantially inflexible aeroplane supplemented by comparatively small relatively movable auxiliary planes forming tips local to the outer margins or lateral wings of said aeroplane and arranged to be shifted relatively thereto but maintained in substantially parallel relation therewith, said auxiliary planes being so arranged as to be capable of closely approaching the main aeroplane, whereby their surfaces may be shielded and rendered ineffective, so as to present to the supporting components of the air, an effective surface equivalent to the aeroplane *per se*.

This invention further includes the various novel features of construction and arrangement hereinafter more definitely specified and claimed.

In the accompanying drawings, Figure 1 is a side elevation of a flying machine of the monoplane type, conveniently embodying my improvements; Fig. 2 is a plan view of 80 the machine shown in Fig. 1; Fig. 3 is a front elevation of said machine; Fig. 4 is an enlarged fragmentary side elevation of the front portion of said machine showing the aeroplane and its relatively movable 85 auxiliary planes; Fig. 5 is a fragmentary view similar to Fig. 4, but showing the relatively movable auxiliary planes shifted to increase the effective weight supporting surface; Fig. 6 is a view similar to Fig. 4 showing the auxiliary planes collapsed and shielded by the aeroplane; Fig. 7 is a side elevation of a flying machine of the monoplane type embodying a modified form of 90 my invention; Fig. 8 is a plan view of the 95 machine shown in Fig. 7; Fig. 9 is a front elevation of the machine shown in Figs. 7 and 8; Fig. 10 is a plan view of a flying machine of the biplane type embodying a convenient form of my invention; Fig. 11 is a 100 front elevation of the machine shown in Fig. 10; Fig. 12 is an enlarged fragmentary side elevation of the machine shown in Figs. 10 and 11; and Fig. 13 is a perspective view of the auxiliary plane and its supports 105 shown in Fig. 11, including additional plane surfaces.

The form of this invention shown in Figs.

1 to 6 inclusive, conveniently comprises a monoplane type of flying machine, to the main frame 14 of which is attached the aeroplane, comprising the laterally extending 5 wings 16, which may be flat or curved as desired. The main frame 14 is provided with the rearwardly extending frame 17, which supports the vertically and horizontally extending rudders 18 and 19 respectively, said 10 rudder 18 being suitably pivoted on the vertical axis 20, and the rudder 19 being pivoted on the horizontal axis 21.

The rudder 18, which is actuated to steer the machine, and thereby determine its 15 course, is arranged to be controlled by the connectors 23 and 24, and the rudder 19, which is actuated to regulate the angle of incidence of the aeroplane wings is controlled by the connectors 25 and 26, all of 20 which connectors extend to a convenient position with respect to the aviator's seat 28, and are connected to be actuated by the hand levers 30 and 31, in any convenient manner.

The machine is arranged to be conveniently propelled in the direction indicated by the arrow in Fig. 2, by the screw propeller 33, whose shaft 34 is horizontally journaled in suitable bearings 35 in the frame 14, and connected to be driven by a suitable motor 30 36, suspended in the frame of the machine.

In order that the aviator may maintain lateral stability of the machine, auxiliary relatively movable planes or wing tips 38 and 39, are provided at or near the opposite sides 35 of the aeroplanes or wings 16. Said auxiliary planes 38 and 39 are pivotally connected at the opposite ends of the levers or supports 40 and 41, which latter are respectively pivoted to the frame 14, for oscillation on the 40 respective trunnions 42 and 43.

As best shown in Figs. 1 and 4, the planes 38 and 39 are normally maintained in an intermediate position extended from the plane 16, and as best shown in Figs. 1 and 2, the 45 planes 39 are connected by the cord or other suitable connector 45 and its branches 46, said connector passing over suitable pulleys 47 and 48, and its branches passing over the pulleys 49 and 50. The auxiliary plane 38 50 at each side of the plane 16 is connected at its rear corners by a cord or connector 52 and its branch 53, which respectively pass over the pulleys 55 and 56 and are connected with the rocker arm 58. Said rocker arm 55 58 is controlled by the hand lever 59, which is located near the aviator's seat 28, and said lever and rocker arm are connected by the rock shaft 60.

The shifting of the hand lever 59 toward 60 the left with respect to Fig. 2 projects the auxiliary plane 38 at the right hand side of said figure forwardly and relatively shifts the auxiliary plane 39 at the same side, backward until the supports 40 and 41 are 65 in a substantially vertical position as in-

dicated in Fig. 5 of the drawings. By the connection above described the movement of the auxiliary planes 38 and 39 at one side of the plane 16, contemporaneously shifts the auxiliary planes 38 and 39 at the other side 70 to a shielded position adjacent to said aeroplane 16, as indicated in Fig. 6 of the drawings.

It will thus be obvious that any movement of the lever 59 to project the auxiliary planes 75 at one side of the aeroplane to any extent will simultaneously withdraw the auxiliary planes at the opposite side of said plane, and that by supporting said auxiliary planes upon the pivoted supports 40 and 41 as 80 shown in Fig. 1, said auxiliary planes 38 and 39 are constantly maintained in a substantially parallel relation to the aeroplane 16 and consequently at the same angle of incidence to the direction of travel of the machine, irrespective of their relative projected or retracted positions, so that as may be observed, the weight supporting surface at the opposite sides of the machine, is contemporaneously increased and decreased respectively. 85

Furthermore, when drawn close to the aeroplane or wings, the wing tips are shielded so that no greater active supporting surface is presented to the air than were the 90 wings alone present; when extended, however, the wing tips are projected in contact with the free air, and exert a lifting effect proportionate to their size. 95

The form of this invention shown in Figs. 100 7 to 9 inclusive, illustrates a monoplane type of machine similar to that shown in Figs. 1 to 3 inclusive and comprises the frame 65, to which is attached the aeroplane, having the laterally extending wings 67. The lateral 105 stability of the machine shown in said figures is maintained by auxiliary planes or wing tips 68, which normally extend beyond the side edges of said wings 67, and which are slidably mounted to reciprocate in close 110 proximity with respect to said wings, in guides 70, which are mounted on the frames 65. Said auxiliary planes 68 are connected by the links 71 with the lever 72, whereby any movement of said lever 72 in either 115 direction contemporaneously shifts one of the auxiliary planes or wing tips 68 outwardly, and withdraws the other wing tip 68, to respectively increase the weight supporting surface of that side of the aeroplane 120 wings 67, where the wing tip is extended, and to decrease the weight supporting surface of the other side of said aeroplane wing where the wing tip is withdrawn. 125

This invention may be conveniently adapted to a flying machine of the biplane type, illustrated in Figs. 10 to 13 inclusive, wherein the frame 75 carries the upper and lower aeroplanes 76 and 77 respectively, which, as best shown in Fig. 12, are curved 130

preferably upwardly toward the direction of travel of the machine. Said aeroplanes may be supplemented by auxiliary planes or wing tips 78 which normally extend beyond the side edges of the opposite wings of said aeroplanes, and which are conveniently supported at or near their four corners by the movable stanchions 80 and 81, which are pivoted at 83 and 84 to the frame 75 of the machine. The auxiliary planes or wing tips 78 are arranged to be shifted transversely with respect to the direction of travel of the machine, but maintained by the movable stanchions 80 and 81 in substantially parallel relation with the aeroplanes 76 and 77, and consequently at the same angle of incidence with respect to the direction of travel of the machine, irrespective of its position with respect to said aeroplane. Said aeroplanes 78 are conveniently connected by the cord or connector 85 and its branches 86, respectively passing over the pulleys 89 and 90, and said planes are respectively connected at their inner corners with the controlling lever 92, by the cords or connectors 93 and 94, respectively passing around the pulleys 95 and 96, which are disposed at the opposite extremities of the frame 75.

30 By the connections above described it may be seen that the auxiliary planes 78 are contemporaneously shifted in the same direction transversely to the direction of the motion of the machine, by any movement of the controlling lever 92, so that when one auxiliary plane 78, for instance at the right hand side with respect to Fig. 11 is shifted outwardly to increase the weight supporting surface, auxiliary plane 78 at the opposite side of the machine is withdrawn, and thereby shields that portion of the aeroplane 76 which it underlies.

In the perspective view shown in Fig. 13, the frame of the auxiliary plane 78, comprising the movable stanchions 80 and 81, is provided with the substantially vertical webs or planes 98 disposed in angular relation with respect to the auxiliary planes 78 and the planes 76 and 77, whereby the adjustable area of the supporting surface is augmented.

55 In order to more fully understand the working of the machines above described, suppose that, owing to an eddy current in the air, or other disturbing influence, the air pressure upon one side of the machine, for instance the right, suddenly becomes less than that upon the left, with the result that the machine tilts to the right upon an axis parallel with the direction of flight of the 60 machine; whereupon the controlling lever may be shifted to the right to extend the wing tip at that side and withdraw the wing tip at the other side, thus increasing the supporting surface upon the side where the 65 pressure is low, and decreasing said surface

on the side where the pressure is high, until the pressures at the opposite sides of the machine become equalized and the equilibrium of the machine is restored. When the disturbing influence returns to normal condition, and the aeroplane has been brought back to even keel, the wing tips may be then shifted back to their normal positions, so as to equalize the areas on both sides of the machine. It is obvious that in the arrangement above described, the angle of incidence presented by the auxiliary planes or wing tips to the air in the direction of the motion of the machine is substantially identical with the angle of incidence of the aeroplanes 76 and 77, and therefore follows that the vertical and horizontal components of the air pressure hold the same relation to each other on both sides at all times, both as regards the wing tips and the main wings, and this ratio is unaffected by any movement imparted to the wing tips by the controlling lever. Hence when the wing tip on one side is extended, and that on the other side withdrawn, in equalizing the supporting effect upon both sides, the horizontal component of the air pressure is also equalized upon the two sides, and therefore all tendency for the machine to swerve from its course is substantially negligible.

95 It is obvious that wings and auxiliary tips as herein described may form the balancing means in other classes of flying machines. For instance, in machines of the polyplane type or in machines of the type 100 wherein the weight supporting surface is not wholly relied upon for maintaining the machine suspended in the air, and therefore it is not desired to limit this invention to the precise details of construction and arrangement herein set forth, as it is obvious that various modifications may be made therein without departing from the essential features of my invention as defined in the appended claims.

110 Having thus described my invention, 11 claim:

1. An aeroplane having means for increasing the supporting surface at one side and contemporaneously decreasing the supporting surface at the other side, each by means of local parallel planes, said planes being at all times parallel to the aeroplane and arranged to be variably spaced from its surface.

115 2. An aeroplane having a plurality of relatively movable auxiliary parallel planes adjacent to its lateral extremities, means directing the movement of said auxiliary planes into position spaced from the surface 120 of said aeroplane to increase the supporting surface and to be shifted adjacent to the surface of said aeroplane and shielded thereby, and means connected to contemporaneously actuate said auxiliary planes relative 125 130

to said aeroplane and contemporaneously extending one thereover and withdrawing another into position to be shielded thereby.

3. In a flying machine, the combination with an aeroplane having laterally extending rigid wings, of auxiliary planes vertically movable relative thereto, in the direction of flight on parallel pivoted supports.

4. In a flying machine, the combination with an aeroplane, of parallel supports pivoted to said aeroplane, and auxiliary planes pivotally carried by said supports and co-operative with said aeroplane at the ends thereof to relatively increase and decrease 15 its weight supporting surface at predetermined localities.

5. In a flying machine, the combination with rigid aeroplanes, of auxiliary planes movable with respect thereto and disposed above and below said respective aeroplanes, pivoted supports for said auxiliary planes, arranged to be shifted to move said auxiliary planes oppositely relative to said aeroplanes and to maintain said planes in substantially parallel relation irrespective of their relative positions.

6. In a flying machine, the combination with aeroplanes, of relatively vertically movable auxiliary planes disposed below and above said aeroplanes, pivoted supports for said auxiliary planes arranged to maintain said auxiliary planes substantially parallel with respect to said aeroplanes, irrespective of their relative positions.

35 7. In a flying machine, the combination with rigid aeroplanes, of auxiliary planes disposed below and above said aeroplanes and normally supported in a position extended therefrom, and means arranged to reciprocate one of said auxiliary planes upward and the other auxiliary plane downward with respect to said aeroplanes, and to shift said auxiliary planes adjacent to said aeroplane to be shielded thereby.

45 8. In a flying machine, the combination with rigid aeroplanes, of relatively movable auxiliary planes disposed below and above said aeroplanes and normally supported in spaced relation thereto, means arranged to 50 shift said auxiliary planes in opposite directions into adjacent relation to said aero-

plane to be shielded thereby, and means operative to maintain said auxiliary planes in parallel relation with said aeroplane irrespective of their position.

55

9. In a flying machine, the combination with aeroplanes of relatively movable auxiliary planes disposed above and below said aeroplanes, pivoted supports arranged to maintain said auxiliary planes substantially parallel with respect to said aeroplanes irrespective of their positions.

10. In a flying machine, the combination with an aeroplane, of auxiliary planes movable with respect thereto, pivoted supports 65 for said auxiliary planes, movable to project them into relatively different planes parallel with said aeroplane, means arranged to shift said supports to project one auxiliary plane and to withdraw the other auxiliary plane 70 with respect to said aeroplane, and arranged to shift said supports to retract said planes alternately to a position adjacent to said aeroplane and shielded thereby.

11. In a flying machine, the combination with aeroplanes, of relatively movable auxiliary planes, parallel pivoted supports for said auxiliary planes disposed local to the lateral extremities of said aeroplanes, arranged to maintain said auxiliary planes in 80 substantially parallel relation with respect to said aeroplane irrespective of their relative positions.

12. In a flying machine, the combination with an aeroplane, of auxiliary planes disposed at the opposite end portions of said aeroplane, pivoted supports for said auxiliary planes, means connected to contemporaneously vertically reciprocate one of the said auxiliary planes downward and the 90 other upward relative to said aeroplane to respectively increase and decrease the weight supporting surface at the respectively opposite end portions of said aeroplane.

In testimony whereof I have hereunto set 95 my hand this 17 day of February A. D. 1910.

EDWARD WANTON SMITH.
